UNITED STATES PATENT OFFICE.

WILLIAM T. WATERS, OF ATLANTA, GEORGIA.

ELECTRICAL RAILROAD-SIGNAL.

SPECIFICATION forming part of Letters Patent No. 314,763, dated March 31, 1885.

Application filed April 1, 1884. (No model.)

To all whom it may concern:

Be it known that I, WILLIAM T. WATERS, a citizen of the United States, residing at Atlanta, in the county of Fulton and State 5 of Georgia, have invented certain new and useful Improvements in a System of Electric Signals for Railways, of which the following is a specification, reference being had therein to the accompanying drawings.

10 My invention relates to improvements in electric railway-signals, the object of which is to provide a system of automatic signals for railways suitable for and applicable to all the purposes for which stationary railway-signals 15 are required and used. The objects sought for I attain by means of the mechanism and electrical connections illustrated in the accompanying drawings, in which—

Figure 1 is a side elevation, partly in section, of the signal-box. Fig. 2 is a front elevation, partly in section, of same. Fig. 3 is a plan view of same on line 3 of Fig. 2, showing the upper bearings of the three signals. Fig. 4 is a plan view of a portion of the signal-actuating mechanism, showing the insulated electric switches. Fig. 5 is a plan view of the power-receiving mechanism, showing the advance signal-releasing magnets with their armatures, the switch-controlling magnets of the motor-circuits, and the cut-out of the signaling-circuit. Fig. 6 is a plan view of the power-releasing magnets, showing the free end of the shuttle-arm in section, the cam-plates being broken away to show the shuttle-35 cam and rollers. Fig. 7 is a side view, partly in section, of the power-receiving and signal-actuating mechanisms. Fig. 8 is a front view, partly in section, of a portion of the advance signal-actuating mechanism and the insulated 40 electric switches controlled thereby. Fig. 9 is a front elevation of the power-receiving and power-releasing mechanism and a portion of the advance signal-actuating mechanism. Fig. 10 is a plan view of the beveled 45 sector, rigidly attached to shaft of advance signal. Fig. 11 is a plan view of the upper of a pair of slotted wheels, loosely mounted on the shaft or stud upon which the advance signal shaft is pivotally mounted. Fig. 12 is a plan 50 view of the lower of these slotted wheels. Fig. 13 is a plan view of the rag-wheel, loosely

mounted on the same shaft or stud. Fig. 14 is a vertical section of the advance-signal-actuating mechanism. Fig. 15 is a plan view of the compound beveled sector and crown sector rigidly attached to the shaft of rear signal. Fig. 16 is a plan view of the eccentric boss, rigidly attached to shaft of rear signal. Fig. 17 is a plan view of rag-wheel rigidly attached to shaft or stud upon which the rear-signal shaft is pivotally mounted. Fig. 18 is a vertical section of the rear-signal-actuating mechanism. Fig. 19 is a side vertical section of a portion of the shuttle-arm and a portion of compound wheel of the power-receiving mechanism. Fig. 20 is a front vertical section of same. Fig. 21 is a front elevation, partly in section, of a portion of the shuttle-arm. Fig. 22 is a side vertical section of same. Fig. 23 is a vertical section of the shuttle through line 23 of Fig. 25. Fig. 24 is a vertical section of the shuttle through line 24 of Fig. 25. Fig. 25 is a cross-section of the shuttle, taken on line 25 of Fig. 24. Fig. 26 is a section of a portion of the shuttle-arm, taken through line 26, Fig. 21. Fig. 27 is a section of the shuttle-arm, taken through line 27, Fig. 21. Fig. 28 is a section of the shuttle-arm, taken through line 28, Fig. 20. Fig. 29 is a section of the shuttle-arm, taken through line 27, Fig. 20. Fig. 30 is a view, partly in section, of one of the cam-shafts with signal-locking arm, and cam-sleeve with locking-arm escapement of the advance signal, with insulated electric switches operated thereby. Fig. 31 is a side elevation of the signal-releasing magnet and its armature, the signal-locking arm, the locking-arm escapement, gravity dog with latching-lever and switches operated thereby, and spring-latch, with switch-controlling magnet of motor-circuit and its armature. Fig. 32 is a diagram of the reversible electric motor and its connection, with power-receiving mechanism, and of the electrical connections for signaling and motor circuits, lighting-circuit, and light-controlling circuit. Fig. 33 is a diagram of the electric motor and its connection with power-receiving mechanism, together with the electrical connections for operating special distant signals. Fig. 34 is a perspective view of the track and nine signal-posts, representing two trains moving in one direction and one train

moving in the opposite direction, and showing the positions of the several signals in front and rear of each train.

It is intended that a train moving over a line 5 of railway shall protect itself from collision both in front and rear automatically, maintaining two advance signals continually displayed in front, and one rear signal continually displayed in rear, the former of which 10 are successively concealed as the train passes them, and the latter is concealed only when the receding train has passed out of the block it is designed to protect.

The setting of an advance signal at a second 15 post in front of a moving train completes a circuit from a source of electricity at said second post in front to and through a reversible electric motor located at first post in front of said train, the action of which motor stores 20 power for displaying the rear and concealing the advance signal at that post, and at same time turns the verifying signal at that post to "safety" and holds it there. The train on passing this post releases the power stored by 25 the electric motor, which power, when released, displays the verifying and rear signals, and conceals the advance signal at that post, and at same time connects the advance signaling-circuit with a local source of electricity, dis- 30 playing an advance signal at the second post in advance of the moving train, and also connects a local source of electricity with a rear signaling-circuit, thereby concealing the rear signal at the post last passed.

35 The displaying of an advance signal at the second post in advance of a moving train connects a local source of electricity at said second post with a motor located at the first post in advance of said moving train; but the 40 motor-circuit is automatically broken by the action of the motor itself at the post where such motor is located as soon as the necessary power has been stored, and the breaking of this circuit, which passes through an electro- 45 magnet at the advance post from which current is received, allows the armature of said magnet to rise, and this operation unites or couples together the two normally-independent signaling-circuits which terminate at that 50 post, thus completing the signaling-circuit from the post next to be passed by the train to the second post in advance thereof. These signals are so interdependent that no train can operate a signal at a post where another train 55 has a signal (advance or rear) displayed, thus always securing an entire block between any two trains, whether moving in the same or in opposite directions on the same track. Each advance signal normally held at "safety" is op- 60 erated by trains moving in either direction, and has one of its sides painted red (for instance) and the other white. The mechanism which actuates it for display is in two sets or parts, only one of which operates at one time. 65 Of these parts one turns the red side of the advance signal in one direction, (west, for instance,) and the other turns the red side in the

opposite direction, the white side being in every case turned toward the approaching train by which it was displayed. The advance signal is displayed by normally-stored power released by an electric impulse from a distant point, and is afterward concealed by the display movement of the rear signal. The rear signal is displayed by power stored from 70 an electric motor released by an electric impulse imparted through the track-circuit to the auxiliary circuit by the passing train, and the same movement stores power for concealing said signal. This power last mentioned 75 is released by an electric impulse from a distant point caused by the receding train passing said distant point.

The operation of the motor is dependent upon the position of the advance signal next beyond it, and the direction of its rotation is determined by the direction from which it receives current. Turned in one direction it stores power that, when released, will display an east rear and conceal an east advance signal. Turned in the other direction it stores power that, when released, will display a west rear and conceal a west advance signal, and turned in either direction it will turn the verifying signal from its normal position of "danger" to "safety," in which position it will remain until the power stored at time of its initial movement is released, and in every case the current that drives the electric motor is automatically broken as soon as the required power has been stored thereby. The further rotation of the motor, caused by its momentum at the time when the current is shut off, affects no part of the power-receiving or signal-actuating mechanisms, except the compound wheel and gearing through which the driving-power of the motor is communicated to the power-receiving mechanism, and the position of this wheel will not interfere with the proper working of that mechanism. An 80 electric-lighting circuit, normally open, is provided at each signal box or station, and is so connected through switches operated by the movement of the signals and a source of electricity at that post that a lighting-current 85 will be diverted through an electric lamp whenever an advance or rear signal is displayed on that post; but the lamp will be cut out when neither one of said signals is displayed. The lighting-circuit is further controlled by an independent light-controlling circuit which passes through an electro-magnet at each signal station, the armatures of which magnets are portions of the normally-open lighting-circuits for their respective 90 posts. With a current on this independent light-controlling circuit the magnets through which it passes are energized. Their armatures are attracted. The free ends of said armatures are drawn away from a fixed contact through which the lighting-circuit normally passes in each post, thus breaking the lighting-circuit simultaneously at every post, 95 so that though signals be displayed no light 100

will appear. The object of this independent light-controlling circuit is to enable those using this system of signals to prevent the waste of electric energy by the burning of the light during daytime or when no lights are required, and the cutting off of the lighting-circuit is made dependent upon the presence (rather than the absence) of a current on this independent circuit, in order that any accident to said independent circuit will leave the lighting-circuit turned on, and thus insure the presence of a light when needed. In this independent circuit at each post and station is a cut-out in which a plug connected with a telegraphic outfit may be inserted at any time with or without battery, as required, and this circuit thus used for telegraphic purposes or the sending of an alarm in cases of emergency, or whenever necessary.

For convenience in describing the apparatus, a railroad running east and west may be assumed. The letter E in connection with a figure (thus 2 E) will denote east, and the letter W in connection with a figure (thus 1 W) will denote west. The electric switches and their contacts are lettered E A, (east advance,) E R, (east rear,) W A, (west advance,) W R, (west rear,) in sets corresponding to the signals by the movements of which they are operated, and each set has a separate series of numbers, thus 1 W A, (1 west advance,) &c. The switches pertaining to the lighting-circuit are lettered L, and numbered separately, thus 2 L (2 light.) I can use any source of electricity that is constant and reliable, whether it be a local or storage battery at each post, or a general-supply wire, or a supply-wire in connection with storage-batteries, (the latter method preferred,) and in case of the general-supply wire being used I would prefer an underground cable, as being free from atmospheric disturbances. The use of a general-supply wire or other common source of electricity at each post or station will necessitate, of course, the use of such resistances as will limit the amount of current imparted to any circuit from such common source to the need of that circuit, and in any case I can use the ground or any other return-circuit. For convenience in this description I use the word "ground" for the return-circuit, and in the drawings I have shown the return-circuit as going to ground through the rails of the track.

For draw-bridges, switches, railway-crossings, junction-working, and all cases where it is necessary to display a distant signal normally held at "safety," and afterward desirable to restore such signal to its normal position from the same or from one or more other more or less distant points, I use a special distant signal with power-receiving mechanism similar to what is here shown, so far as similarity is necessary for operating said mechanism in one direction only. An electric impulse from a distant point will display such a signal, and the displaying of it will divert a current from a source of electricity at the signal-post

through a motor at that post, and thence over the single-line wire by which such distant signal-post is connected with the post or station from which such signal is being operated through one or more electro-magnets at that station, for giving an audible or visible verification of the distant signal, and for operating any device in connection with the locking mechanism of drawbridges and switches, as desired, and thence to ground. The motor, in this case, as before, has an automatic cut-out, whereby the driving-current is cut out as soon as the motor has stored the necessary power for concealing the displayed signal. A second impulse from the same or another distant point to the signal-post will pass through a power-releasing magnet at that post and to ground, releasing the stored power, and thereby concealing the displayed signal.

For signal boxes or posts I have shown a box having an iron bed-plate, and in the lower part of which are housed the power-receiving mechanism and electrical appliances, with a door in each side that affords access to these parts when necessary. The upper part is preferably glazed all around, and covered with a metal roof, thus permanently housing the signals from the elements, but at the same time leaving them in plain view from any direction. These boxes are to be mounted conspicuously on any suitable supports located at intervals along and near the line of the track, and at such distances apart and at such distances from the line of the track (not necessarily uniform in either case) as the traffic of each road may require, or the topography of the country through which it passes may render most convenient or desirable. The signaling-circuits, each of which extends only from a given signal-post to the one nearest to it in either direction, are normally independent of each other. They are arranged in series along the line of railway, each series extending from one station or passing-point to another only along tracks over which trains are permitted to run in both directions; but along double-track roads over which trains are permitted to run on a given track in one direction only, a single series may extend from end to end of each of such tracks. In either case, before a train is permitted to enter a series the train-dispatcher, station-agent, or other official of the road charged with that duty, by means of a manual-key located at the initial station, imparts to the signaling-circuit about to be entered two electrical impulses, the first of which displays an advance signal near by, and the next displays a second and more remote advance signal. The displaying of this second signal causes the verifying-signal at first signal-post to be turned to "safety," and the engine-driver is thereby notified that his train may proceed. On leaving or passing out of such a series of circuits there is left behind the train but one signal in an abnormal position, and that a rear signal at the signal-post last passed, and it may be concealed.

by an electric impulse transmitted from a manual switch or key at the terminal station.

It is manifest that initial and terminal impulses may be transmitted from track-circuit closers operated by the movement of the train itself, if this mode is, in any case, preferred to the manual switches or keys above referred to. A single conductor for both motor and signaling circuits is required for each track, whether trains move in both or in one direction only over said track, and a single supply-wire and a single light-controlling circuit is required for each road regardless of the number of tracks. For track-circuit closers I may use any of the well-known forms.

Referring to the drawings, the railway-track A, Fig. 32, is provided at any suitable intervals with track-circuit closers B, (of any approved pattern,) so adjusted with reference to one rail of the track that the passage of a locomotive or car, or of the locomotive and cars composing a train, will complete a local circuit at the signal-post C through the circuit-closer B, a source of electricity, B', the electro-magnet D, and the wires connecting them. The closing of this circuit causes the magnet D to attract its armature, which is part of an auxiliary circuit that includes the magnets D D' D'', the armature of the magnet D and its contact E, the movable brush or strip E', its fixed contact or strip E'', a source of electricity, and the wires by which they are connected. The armatures of the magnets D D'' have each a hook or shoulder formed on the free end thereof, with which the long arm of the two-armed levers F F' are normally engaged. The levers F F' are pivoted at their angle, and provided with retracting springs F', having a tendency to hold them in their normal positions. These armatures also carry at their free ends each an insulated flexible strip, F'', which are electrically connected by flexible conductors with the binding-screws 1 E 1 W, respectively. The strips F'' are provided with an upper contact each, 2 E and 2 W, and a lower contact each, 3 E and 3 W, and are normally held against the upper of their respective contacts; but when the armatures to which they are attached are attracted by the closing of the auxiliary circuit their contact with 2 E and 2 W is broken and their contact with 3 E and 3 W is established.

Adjacent to and between the two levers F F' is a two-way-reciprocating power-receiving mechanism, Fig. 5, pivoted upon the shaft G, and consisting of a pair of loosely-mounted arms carrying the heavier weights H H', a pair of loosely-mounted arms carrying the lighter weights H'' H''', the loosely-mounted bifurcated two-armed lever I, the loosely-mounted compound wheel J, the rigidly-mounted shuttle-arm K, the rigidly-mounted two-armed weight-raising lever L, and the rigidly-mounted insulated brush or strip E'. The shaft G is supported in suitable bearings fastened to the bed-plate or floor of the signal-box. The bifurcated two-armed lever I is piv-

oted loosely at its angle on the shaft G, and each of its arms, at its outward extremities, is fitted with a latch, I' and I'', respectively, adapted to engage, and normally engaged with, the short arms of the levers F F', respectively, but in such manner as to effect only the downward movement of said latches. Each of these latches is pivoted and provided with a retracting-spring, I', having a tendency to hold the latch in its normal position with respect to the arm on the end of which it is pivoted. Each arm of this lever is also fitted at its extremity with a downward-projecting hook, I''. At the shaft G the lever I has two bearings, between which are mounted the shuttle-arm K and the compound wheel J. One of these bearings extends upward and carries the beveled sector I''. The arms of the lever I also carry the weight-raising projections I'' I'', respectively, projecting at right angles to the vertical plane of said lever. The arms carrying the lighter weights H'' H''' rest in the path of these projections I'' I'', and in such position that one or the other of them is raised whenever the lever I is moved from its normal position. The compound wheel J is loosely mounted at its center upon the shaft G, and its face is divided circumferentially into two parts, one part, J'', being like the face of any ordinary worm-wheel, the other presenting a preferably flat smooth surface with one or more radially-projecting teeth, J''. The shuttle-arm K is rigidly pivoted to the shaft G, and carries at one end the beveled sector K''. Its other end is bored and slotted to receive the shuttle K', its cam-rollers K'', the shuttle-bolt K'', and its cam-rollers K'', Figs. 19 to 22. The normal position of the shuttle-arm is perpendicular to the horizontal plane of the shaft G, with the beveled sector K'' above and the bored and slotted end below said plane, and in this position the shuttle-bolt K'' at its inner end is in the path of the radially-projecting teeth J'' of the compound wheel J, and held there by the shuttle-spring K''. The shuttle-bolt K'' is fitted with two stops, between which the spring K'' is mounted, said spring resting against a washer at each end, and thereby confined, under a slight compression, between said stops. The ends of the shuttle K' are bored, Figs. 19 to 29, to accommodate the movement of the bolt K'', and slotted to permit the stops on said bolt to pass through.

On the shuttle K' are formed laterally-projecting studs K'', parallel to the shaft G, which slide in slots in the arm K, and, projecting beyond the surface of said arm, form bearings by which the shuttle can be moved longitudinally within said arm.

On the shuttle-bolt K'' are formed laterally-projecting studs K'', also parallel to the shaft G, and adapted to slide in slots in the arm K, but projecting beyond the outer surface of the said arm, whereby the bolt K'' may be moved longitudinally within the shuttle K', or held at a fixed distance from the shaft G while the

position of the shuttle itself is being changed. The two-armed weight-raising lever L, Fig. 5, is rigidly pivoted at its angle to the shaft G, and each arm has a lateral projection, L¹ L², at right angles to the vertical plane of said lever. The arms carrying the heavier weights H H' rest in the path of these projections, and in such position that one or the other of them will be raised whenever the shaft G is turned from its normal position. The movable brush or strip E is rigidly pivoted at one end upon, but insulated from, the shaft G, and in its normal position its free end rests upon an insulating-surface; but when moved from this position it passes off the insulating-surface and upon the metal surface of the insulated semi-annular strip E'. The beveled sector K⁶, Fig. 7, meshes with a beveled sector, M, rigidly mounted on the shaft N of the verifying-signal. This shaft is held in its position by suitable bearings, as at O O'. The beveled sector I³ meshes with the beveled wheel M', which is rigidly mounted on the shaft N'. Through this shaft N' motion is communicated from the shaft G of power-receiving mechanism to the rear and advance signal mechanisms.

To the compound wheel J is geared a reversible electric motor, P, Fig. 32, having no dead-centers.

30 Fixed to the bed-plate of the power-receiving mechanism are the two cam-plates Q Q', each having an eccentric groove or bearing, Q', Figs. 7 and 9, in which the projecting lugs K² of the shuttle K' are adapted to move, and 35 two concentric bearings, Q² Q³, on which the projecting lugs K⁴ of the shuttle-bolt K³ are adapted to move. The bearings Q³ are cut away at the limit of the upward movement of the lugs K⁴ in either direction to allow said 40 lugs K⁴ to pass from the inner bearing, Q², to the outer bearing, Q³, and are also cut away at the limit of the downward movement of the lugs K⁴ to allow them to pass from the outer bearing, Q³ to the inner bearing, Q².

45 Cam-rollers may be used on the lugs or studs K² and K⁴, if found to be desirable, and I have shown that construction.

On the shaft N', at its upper end, is rigidly mounted a rag-wheel, R, Fig. 7, carrying a 50 chain belt, R², through which motion is communicated to another rag-wheel, R', loosely mounted on the fixed shaft N². The rag-wheel R has formed on its upper face radial ribs or projections or lugs R³.

55 The shaft N³ of the rear signal is mounted pivotally, Fig. 18, upon the top of the shaft N', and is held in an upright position by a suitable bearing, O', at the top, as shown, Fig. 3.

60 Mounted rigidly upon and at the bottom of the shaft N³ is the boss S, carrying the downward projection S' in the path of the ribs or projections or lugs R³ of the rag-wheel R. On same shaft and immediately above this boss is the cam T, the beveled sector U, and the crown-sector U'. The beveled sector U, Fig. 7, meshes with the beveled sector V, which is rigidly mounted on the inner end of the cam-

shaft W. On the outer end of this cam-shaft is rigidly mounted an arm carrying the weight H'. The cam-shaft W is in its normal position when this weight is at its lowest point, and has a three-eighths turn movement, more or less, in either direction from its normal position.

Between the beveled sector V and the weight H' are arranged five insulated electric switches, (shown in plan view in Fig. 4, and diagrammatically in Fig. 32,) two of which are disturbed by a movement of the cam-shaft W in one direction only, two more are disturbed by a movement of the cam-shaft W in the other direction only, and one (2 L, Fig. 4) is disturbed by a movement of said cam-shaft in either direction. Each of these switches is provided at its free end with an upper and a lower contact, Fig. 32, between which it is adapted to move, and each is normally held against its lower contact; but a movement of the cam-shaft W in either direction will so move three of the switches as to force them away from their lower contacts and against their upper contacts, the other two switches remaining meanwhile in their normal position.

65 Around the cam T passes the eccentric-strap X, Figs. 4 and 7, which is bent to pass the shaft N of the verifying-signal and terminates in a bolt, X', passing through the bearing X² in proximity to the wheels Z Z' of advance-signal mechanism, with both of which said bolt is thrown into engagement by the displaying of the rear signal; but normally it is not so engaged. The crown-sector U, with two notches formed therein at points diametrically opposite to each other, Fig. 32, is adapted to engage with the hook or shoulder on the armature of the magnet D⁶. It is not normally so engaged, but a quarter-turn of the shaft N³ in either direction from its normal position will allow the hook of the depressed armature to rise into one or the other of the notches U² U³ of the crown-sector U', locking it in that position.

70 On the shaft N² are loosely mounted the rag-wheel R' and the slotted wheels Z Z', Figs. 7 and 14. On the upper side of the rag-wheel R' is formed a recess, and in this recess is the loose arm Y, Fig. 13, pivoted about the shaft N², and having a reciprocating movement within said recess. On the upper surface of this arm are two perpendicular projections, Y' Y². Around five-eighths, more or less, of the peripheries of the wheels Z Z' are formed beveled teeth, Figs. 11 and 12. The remainder of their peripheries is smooth, with a single notch in each to receive the bolt X'. The wheel Z, Figs. 12 and 14, carries a short downward projection, a, located in the path of the projection Y², and a longer upward projection, b, the latter extending upward through a slot in the wheel Z' and above its surface. The wheel Z', Figs. 5, 11, and 14, carries a long downward projection, a', and a shorter upward one, b', the former extending down-

ward through a slot in the wheel Z and into the path of the projection Y' . The shaft N^4 of the advance signal is mounted pivotally upon the top of the shaft N^2 , Fig. 14, and is held in an upright position by suitable bearings, as shown, Fig. 3. On the shaft N^4 is rigidly mounted the beveled sector U^4 , on the under side of which are the downward projections $c c'$, located in the paths of the projections $b b'$. The beveled sector U^4 meshes with the beveled sector V' , Fig. 7. This last is rigidly mounted on the inner end of the cam-shaft W' , on the outer end of which is rigidly mounted an arm carrying the adjustable weight H^6 , the normal position of which is that which it would assume under the law of gravity.

Between the sector V' and the weight H^6 is a single insulated electric switch, 1 L, provided at its free end with an upper and a lower contact, between which it is adapted to move. It is normally held against its lower contact, but a movement of the cam-shaft W' in either direction from its normal position will force it away from its lower contact and against its upper contact.

On either side of and at right angles to the vertical plane of the cam-shaft W' , and in the vertical plane of the shafts $N^2 N^4$, are the cam-shafts $W^2 W^3$ of the two sets of advance-signal-actuating mechanism. As these are similar in construction and operation, I will describe but one of them.

On the inner end of the cam-shaft W^2 is rigidly mounted the beveled sector d , meshing with the slotted wheel Z , and on its outer end is rigidly mounted an arm carrying the weight H^4 and the signal-locking arm e , Figs. 7 and 32, adapted to engage and normally engaged with the hook or shoulder formed on the armature f of the electro-magnet D^3 . There is also loosely mounted on the cam-shaft W^2 the cam-sleeve g , Fig. 30, carrying the locking-arm escapement h , and an arm carrying the weight H^8 . The locking-arm escapement h is adapted to move behind and parallel to the path of the signal-locking arm e , and is normally at rest against it. Said locking-arm escapement has formed on it and projecting at right angles to the plane in which it moves four lugs, $i i^2 i^3$. Of these two—viz., i^2 and i^3 —are short, and two—viz., $i i'$ —are long.

To the lug i' is attached an insulated strip or spring, 16, adapted to make contact with the fixed contact-point 17, but normally out of contact therewith.

The armature f of the magnet D^3 has a hook or shoulder formed both above and below on its free end, and the lower one is extended horizontally at right angles to said armature.

When the mechanism is in its normal position, the signal-locking arm e is engaged with the armature f of the magnet D^3 , and the locking-arm escapement h is held away from said armature by the lug i , resting against the locking-arm e ; but if the armature f is depressed, the signal-locking arm e is released, and, im-

peled by the suspended weight H^4 , makes its forward movement with the cam-shaft W^2 . The cam-sleeve g , impelled by its suspended weight H^8 , also moves forward; but its movement is immediately arrested by the lug i' striking against the hook on the under side of the depressed armature f . In this position the spring or strip 16 is resting against the fixed contact 17. If the armature be now allowed to rise, it will move out of the path of the lug i' and into the path of the lug i^2 . The cam-sleeve g will make a second short movement, but is again stopped by the lug i^2 striking against the hook on the upper side of the restored armature f . If the armature f is again depressed out of the path of the lug i^2 , the cam-sleeve g will make a forward movement, but is again stopped, this time by the lug i^3 striking against the hook on the under side of the depressed armature f ; and now, if said armature be allowed to rise again out of the path of the lug i^3 , the cam-sleeve g will complete its forward movement, following up and finally resting against the signal-locking arm e , and the restoration of said locking-arm e to its normal position will restore the locking-arm escapement h to its normal position also.

The cam-sleeve g has formed on it two standards, j , between which is pivoted a gravity-dog, k , Fig. 31, in such position that the second forward movement of the cam-sleeve g will carry said gravity-dog k through and beyond that portion of its path in which normally rests a locking-lever, l , and, depressing it, will leave its free end engaged with a spring-latch, m , adapted to engage therewith at the limit of the downward movement of said locking-lever l . The free end of said lever is rigidly connected with the free ends of the switches 4 E A, 5 E A by a connecting-rod, n , pivoted to the lever l and to a cross-bar, n^2 , that is connected with but insulated from both of said switches; so that when the lever l is depressed the said switches are likewise depressed, and when the lever is allowed to rise the switches rise with it.

Below the lever l in same vertical plane with it, and with its free end in same direction as that of said lever, is the armature o of the electro-magnet D^6 . This armature is so connected with the locking-lever l that the depression of said lever will not change the position of said armature; but when both are depressed, the lever cannot rise till the armature be allowed to rise also. If the lever l be depressed, it makes engagement with the spring-latch m , and depresses the switches 4 E A, 5 E A, as above set forth, breaking the contact of the former with 12 E A, and establishing the contact of the latter with 13 E A, and they will be so held; and now, if the armature o be depressed, its free end passing over a cam formed on the spring-latch m will force said latch outward, releasing the lever l from said latch; but as the said lever cannot rise while the armature is depressed, it is now held down by the armature, and when the armature is al-

lowed to rise to its normal position the lever *l* and the switches 4 E A, 5 E A, with which it is connected, will rise to their normal positions. The cam-sleeve *g* has also formed on it a cam 5 in such position that the fourth and final forward movement of said cam-sleeve will bring said cam into that portion of its path in which the insulated electric switch 6 E A normally rests, raising it away from its lower contact, 10 E A, and against its upper contact, 14 E A. The cam-shaft *W*² has also formed on it a cam in such position that its forward movement will bring said cam into that portion of its path in which normally rest the insulated 15 electric switches 1 E A, 2 E A, 3 E A, raising them away from their lower contacts, 8 E A, 10 E A, and 11 E A, and against their upper contacts, 7 E A, 9 E A, and the upper contact of 3 E A, respectively. The latter being 20 merely a stop, and having no electrical connection, is not shown in diagram of circuits, Fig. 32.

The cam-shafts *W*² *W*³, their cam-sleeves *g*, *g'*, and all their electrical and mechanical connections are similar, one being connected with the slotted wheel *Z* for advance signals of trains moving in one direction, the other being connected with the slotted wheel *Z'* for advance signals of trains moving in the opposite 30 direction. The cam-shaft *W*³ has the locking-arm *e* engaged with armature *f*' of magnet *D*³, the cam-sleeve *g'* with locking-arm escape- 35 ment *h*', locking-lever *l*', spring-latch *m*', connecting-rod *n*', armature *o*' of magnet *D*³, and switches and their contacts, numbered as before, but designated by the letters W A, instead of E A, as before. In other respects the description above given of *W*² and its connections will apply to *W*³ and its connections.

40 On the shaft *N*, Fig. 32, of the verifying-signal is rigidly mounted the double cam *p*, in proximity to which and in its path normally rest the insulated electric switches *q* *q'*, their free ends pressing against the contacts *r* *r'*, and in such position with respect to each other that the turning of the shaft *N* in either direction from its normal position will force said switches away from said contacts. There is also rigidly mounted on this shaft, or on the 45 shaft *G*, as may be most convenient, the automatic cut-out *P'*, Fig. 32, of motor circuit. The armature of the magnet *D*' carries at its free end an insulated strip, *F*³, which is electrically connected with the fixed contact 1 E. 50 Near and in the path of this strip are the contacts 2 E 3 E, between which it is adapted to move, and against the former of which it is normally at rest.

The armature of the magnet *D*' and its strip 55 *F*³ and contacts 1 W, 2 W, and 3 W are similar in construction and operation to those of the magnet *D*', just described.

The electrical connections of each signal-post are as follows: The track-circuit closer B 60 is the normally-open point in a local circuit that includes a source of electricity, *B*', and an electro-magnet, *D*. The contact 1 T is con-

nected, through the source of electricity *B*' and the magnet *D*, with the contact 2 T. In the auxiliary local circuit there are two normally-open 70 points. One pole of the source of electricity is connected through the magnet *D* with the fixed contact *E*. The other pole of the source of electricity is connected through the magnet *D*² with the movable brush or strip *E*'. The fixed contact or strip *E*² is connected, through the magnet *D*', with the armature of the magnet *D*. If, now, the brush or strip *E*' be brought into contact with the metal surface of the strip *E*², and the armature of the magnet *D* be depressed 80 against the contact *E*, the auxiliary local circuit will be closed. The closing of this circuit will excite the magnets *D*' *D*², and their armatures will be attracted, and any power that may have been stored in the power-receiving mechanism will be released. The armature of the magnet *D*' being attracted, the insulated strip connected with line eastward, for instance, will be drawn away from the contact 2 E and against the contact 3 E, and 85 so remain until the movable strip *E*' moves off the metal surface and upon the insulating surface of the fixed strip or contact *E*². The magnet *D*², its armature, and strip *F*³ and its contacts 1 W, 2 W, and 3 W will be similarly 90 affected at same time. The strip *F*³, attached to armature of magnet *D*', is connected through the fixed contact 1 E directly with line-wire of signaling-circuit in one direction, and the strip *F*³, attached to armature of magnet *D*², is 95 connected through the fixed contact 1 W directly with line-wire of signaling-circuit in the opposite direction. *r* is connected with 1 W R, *r'* with 1 E R. 2 E R is connected with *q*', 2 W R with *q*. 4 E R is connected with 8 E A, 4 W R with 8 W A. 5 E R is connected with 9 E A, 5 W R with 9 W A. 1 E A is connected with 2 E A, 1 W A with 2 W A. 4 E A is connected with 6 E A, 4 W A with 6 W A. 11 E A is connected with ground, 11 W A with ground. 3 E R and 3 W R are connected with one end of the coils of the signal-controlling magnet *D*³, the other end of which is connected to ground. 7 E A is connected with 3 E A, with 16 E A, and with one 100 end of the coils of the signal-controlling electro-magnet *D*³, the other end of which is connected with 10 W A. 7 W A is connected with 3 W A, with 16 W A, and with one end of the coils of the signal-controlling electro-magnet *D*⁴, the other end of which is connected with 10 E A. 5 E A is connected, through the coils of the switch-releasing magnet *D*⁴, with one pole of a source of electricity the other pole of which is connected to ground. 5 W A 105 is connected, through the coils of the switch-releasing magnet *D*⁴, with one pole of a source of electricity, the other pole of which is connected to ground. 14 E A and 14 W A are connected, through the reversible electric motor *P* and the automatic cut-out *P'*, with ground. 15 E A is connected with *q*', and 15 W A with *q*. 12 E A is connected with 2 E and with 13 W A. 12 W A is connected with 2 W and

with 13 E A. 17 E A and 17 W A are connected with ground.

The signals are all two-way reciprocating, as shown, and of any desired shape and material, thin disks of metal preferred; and they are displayed by turning one side to the view of the engineer, and concealed by turning one edge to his view. The verifying-signal disk s is normally displayed, and when displayed indicates "danger" to an approaching train, and warns the engineer to stop his train before reaching the signal. When concealed, it indicates "safety" to an approaching train, and notifies the engineer that the next block ahead is clear. The advance signal-disk, s' , is normally concealed, and is riveted to that side of its shaft normally farthest from the verifying-signal shaft. One side of it is painted red, for instance, and the other side white. The rear signal-disk, s^2 , is normally concealed, and it is riveted to that side of its shaft normally farthest from the verifying-signal shaft. One side of it is painted blue, for instance, and the other side white. The verifying-signal disk s , at its center, has a perforation or opening, s^3 , to receive the electric lamp t , which is to be suspended therein, and the lighting-circuit of which is as follows: The insulated switches 1 L and 2 L, Fig. 32, are connected with one pole of the lamp, the other pole of which is connected to ground. These switches are provided with an upper and a lower contact each, located near and in the path of their free ends, and against the lower of these (which are merely stops, and not shown in diagram) they normally rest. The upper of these contacts, 3 L 4 L, are connected with the armature of the magnet D^3 of the light-controlling circuit, and through it with one pole of a source of electricity the other pole of which is connected to ground.

It will be observed that the verifying-signal is the main signal of the system. It is the signal by which the engineer is guided, and guided by it he will never see, while running, any advance or rear signals but those of his own train. These he does not heed, and the visible disks of advance and rear signals may therefore be entirely dispensed with along the line of road, except at way-stations or other points where it is desired to give warning, not only of a train's approach, but also to indicate the direction from which it is approaching, and even then very small disks may be used. But while the advance and rear signal disks are entirely subordinate, and may ordinarily be dispensed with to advantage, thus reducing to unity the number of signals presented to the view of the engineer, and reducing materially the size of the signal-box itself, yet the advance and rear signal mechanisms must be retained, for on the proper working of these depends the working of the verifying-signal itself, as we have seen.

The verifying-signal may consist of two disks, one crossing the plane of the other at right angles, as at s^4 , Figs. 1 and 2, and by

painting the sides of this second disk in different colors—one side red, the other side white, for instance—the direction of the train 70 signaled by it will be indicated. These signals are all capable of hand as well as electrical manipulation.

The whole of the mechanism of a signal-box is bolted together in an iron frame-work, as 75 shown, so that the position of the parts with reference to each other is fixed, and the necessity for frequent adjustments thus avoided. The housing of the mechanism is clearly necessary; but the housing of the disks themselves 80 is optional, but preferred.

The lighting-circuit at a post may be made dependent for a current upon the display movement of the advance signal only, and with advantage, generally, since the engineer 85 of a passing train, after passing a given post, has no further need of a light at that post, and a following train must have re-established the lighting-circuit by the display of its advance signal before it reaches such post. If for any 90 reason a lighting-circuit is not deemed advisable, any ordinary lamp may be used in connection with this system for night-signaling. The crown-sector U' may be connected with the cam-shaft W instead of the rear-signal 95 shaft N^3 , and would then be a plain sector with radial notches or recesses in its periphery.

With this construction the operation of the device is as follows: We will suppose a train about to enter a series of signaling-circuits 100 from the west. A current of electricity is imparted to the first signaling-circuit. This current, entering the first signal box or post, Fig. 32, at 1 W, will pass thence through F^3 , 2 W , 4 W, 12 W A, 4 W A, 6 W A, 15 W A, q , r , 105 1 W R, 4 W R, 8 W A, 1 W A, 2 W A, 10 W A, D^3 , 3 E A, 11 E A, and thence to ground. The passage of this current through the magnet D^3 causes it to attract its armature f , thereby releasing the locking-arm e of the east advance signal mechanism, and the cam-shaft W^2 , actuated by the normally-suspended weight H^4 , moves forward at once. The cam formed thereon is forced into that part of its path in which the switches 1 E A, 2 E A, and 3 E A 115 normally rest, raising them away from 8 E A, 10 E A, and 11 E A, and against 7 E A, 9 E A, and the upper contact of 3 E A, respectively. The latter, being merely a stop, is not shown in diagram, Fig. 32. At same time the locking-arm escapement h , actuated by the suspended weight H^3 , is allowed to move forward till the lug i' thereon strikes against the hook or shoulder on the depressed armature f . In this position only, the strip or spring 16 is 120 resting upon the fixed contact 17, which is permanently connected to ground, thus furnishing a temporary ground-connection for the current operating in lieu of that through 3 E A and 11 E A, which is broken by the turning of the cam-shaft W^2 ; but the cam-shaft 125 W^2 has rigidly mounted on its inner end the beveled sector d , Fig. 14, meshing with the slotted wheel Z , the long upward projection b

of which will strike against the downward projection c' of the beveled sector U^4 , thus turning the advance-signal shaft N^4 ninety degrees, or to its eastward "danger" position—that is, with the red side of its disk fronting eastward. It is stopped in this position by the shorter downward projection a of the wheel Z striking against the upward projection Y' of the loose arm Y , in the recess on the upper surface of the rag-wheel R' , at the limit of the movement of the said loose arm Y in accommodating itself to the action of the released and falling weight H^4 . The beveled sector U^4 , Fig. 7, meshes with the beveled sector V' , and through it imparts motion to the cam-shaft W' , raising the smaller weight H^6 , and at same time raising the switch $1 L$ into contact with $3 L$. A lighting-current may now pass from a source of electricity, as at B^2 , to and through the armature $5 L$ of the magnet D^8 , to $6 L$, $7 L$, $3 L$, $1 L$, $8 L$, through the lamp t to $9 L$, and thence to ground. The now suspended weight H^6 will oppose the nearly-fallen weight H^4 and hold the east advance signal and its mechanism in the position to which the latter has forced it. If the signaling-current be now broken at the key, or other circuit-closer employed and the line connected through a gong to ground at the initial station, the armature f of the magnet D^8 will rise out of the path of the lug i' on the locking-arm escapement h , and into the path of the lug i^2 thereon, and the cam-sleeve g , actuated by the weight H^8 , will move forward till the lug i^2 strikes the hook of the restored armature f , thus forcing the gravity-dog k through and beyond that portion of its path in which the locking-lever l normally rests, depressing said lever and forcing it into engagement with the latch m , by which it is held down. The locking-lever l is rigidly connected with the switches $4 E A$ and $5 E A$, Fig. 32, and they are depressed with it, forcing the former away from $12 E A$ and the latter against $13 E A$. A current will now pass from a source of electricity, as at B^6 , at the signal-post to D^6 , $5 E A$, $13 E A$, $2 W$, F^3 , $1 W$, and thence to initial station, through gong, and to ground, giving a verification of the east advance signal just displayed. The passage of this current through the magnet D^6 will cause it to attract its armature o , and its free end, which is preferably provided with a friction-roller, passes over a cam on the latch m , forcing it outward, and freeing the locking-lever l from said latch m , but detaining it in its depressed position by reason of its connection with the now depressed armature o . The armature o is held down by the attraction of the magnet D^6 until the ground-connection at initial station is broken. When this is done, the armature o , the locking-lever l , and the switches $4 E A$ $5 E A$, actuated by the resiliency of the said switches or other suitable means, rise together to their normal positions, re-establishing the contact of $4 E A$ with $12 E A$, and breaking the contact of $5 E A$ with $13 E A$. If, now,

a second electric impulse be imparted from the initial station to the signaling-circuit, it will enter the first signal-box, as before, at $1 W$, and pass thence through F^3 , $2 W$, $4 W$, $12 W A$, $4 W A$, $6 W A$, $15 W A$, q , r , $1 W R$, $4 W R$, $8 W A$, $1 W A$, $2 W A$, $10 W A$, D^3 , $7 E A$, $1 E A$, $2 E A$, $9 E A$, $5 E R$, $2 E R$, q^3 , $15 E A$, $6 E A$, $4 E A$, $12 E A$, $4 E$, $2 E$, F^3 , $1 E$, and thence through second signaling-circuit of the series to the second signal-post, which it will enter at $1 W$, and pass thence through F^3 , $2 W$, $4 W$, $12 W A$, $4 W A$, $6 W A$, $15 W A$, q^2 , q , r , $1 W R$, $4 W R$, $8 W A$, $1 W A$, $2 W A$, $10 W A$, D^3 , $3 E A$, $11 E A$, and thence to ground. The passage of this current through the magnet D^3 of first signal-post causes it to attract its armature f , thus permitting the locking-arm escapement h to make a slight forward movement, the lug i^2 being released; but this movement is immediately arrested by the lug i^3 striking against the shoulder of the depressed armature f . The passage of this current through the magnet D^3 of the second signal-post causes it to attract its armature f , thereby releasing the locking-arm e of the mechanism for an east advance signal and the cam-shaft W^2 actuated by the normally-suspended weight H^4 , moves forward at once, raising the switches $1 E A$, $2 E A$, $3 E A$ out of contact with $8 E A$, $10 E A$, $11 E A$, and into contact with $7 E A$, $9 E A$, and the upper contact of $3 E A$, respectively, (which last, having no electric connection, is not shown in drawings,) at same time the locking-arm escapement h , till now held back by the lug i formed thereon, resting against the signal-locking arm e , is allowed to make a slight forward movement, but is immediately arrested by the lug i' striking against the shoulder of the depressed armature. On the cessation of this current the armatures f of the magnets D^3 of first signal-post and D^3 of second signal-post, actuated by a suitable spring, rise to their normal position. At the first signal-post the lug i^3 of the locking-arm escapement h is released, and the locking-arm escapement completes its movement, following up and finally resting against the signal-locking arm e , which is in the path of the lug i , formed on said locking-arm escapement h , and the cam formed on the cam-sleeve g is brought directly under the insulated switch $6 E A$, raising it out of contact with $15 E A$ and into contact with $14 E A$. At the second signaling-station the lug i' of the locking-arm escapement h is released, and said locking-arm escapement moves forward till the lug i^2 formed thereon strikes against the shoulder of the restored armature f , where its movement is arrested; but in making this forward movement the gravity-dog k passes over the cam formed on the locking-lever l , depressing it, and leaving it engaged with the latch m , passed beyond the path of said cam, so that the locking-lever l may rise as soon as released from the spring-latch m . It is to be remembered that the depression of

the locking-lever l does not disturb the armature o of the magnet D^6 , the rod connecting them passing freely through one or both. Their movement away from each other is limited by the shoulder formed on one end of said bolt and a nut secured to the other end thereof; but their movement toward each other is not limited thereby. With these conditions a current passes from a source of electricity, B^6 , through an electro-magnet, D^6 , switch 5 E A , and the contact 13 E A , 2 W , F^3 , 1 W , to the signaling-circuit westward, which it traverses to the first signaling-station, where it enters at 1 E , and passes thence through F^3 , 2 E , 4 E , 12 E A , 4 E A , 6 E A , 14 E A to one set of brushes of a reversible electric motor, P , through the armature of said motor and the field-magnets thereof, to the automatic cut-out P' , which may be mounted upon either the shaft N of the verifying-signal or the shaft G of the power-receiving mechanism, as may be most convenient, and thence to ground. The passage of this current through the electric motor P will cause it to rotate in a predetermined direction. On the shaft of the rotating armature of said motor is formed a universal screw that meshes with a worm-wheel, J^3 , and the shaft of this worm-wheel has also formed on it a perpetual screw that meshes with the worm-surface J^2 of the compound wheel J , whereby the driving-power of said motor is communicated to said wheel J . The shuttle-arm K of the power-receiving mechanism being in its normal position, with the shuttle-bolt K^3 resting in the path of the radially-projecting teeth J' of the compound wheel J , the rotation of said wheel will bring one of said teeth in contact with K^3 , and thus, through it and the shuttle-arm K in which it moves, communicate motion to said shuttle-arm and to the shaft G on which said arm is rigidly mounted. The shuttle-arm will be moved in the direction of the hook I^4 . The lug L' , Fig. 5, will be brought into contact with the arm carrying the heavy weight H , raising said weight. The beveled sector K^6 , Fig. 7, meshing with the beveled sector M on verifying-signal shaft N , will gradually turn said signal from its normal position of "danger" to that of "safety." The cam-roller K^2 of the shuttle will move in the groove Q^2 of the cam-plates, Fig. 9, and the cam-rollers K^4 of the shuttle-bar will move along the upper bearing of the concentric rib Q^3 , formed on said plates, until the shuttle-arm is in such position that the shuttle-bolt will engage with the hook I^4 of the bifurcated two-arm lever I . At this point the rib Q^3 is cut away, and the shuttle K' , having been forced outward by the eccentric cam Q^2 , has compressed the shuttle-spring K^5 , Figs. 19 and 20, in such direction that the bolt will be forced outward from the shaft G , out of engagement with the wheel J and into engagement with the hook I^4 of the bifurcated two-armed lever I , where it is held, (vide Fig. 9,) the heavy weight H being now suspended. At the same moment the

brush of the motor cut-out P' passes from its metal contact to an insulating surface, breaking the motor-current, and allowing the armature o of the magnet D^6 at second signaling-station to rise, and with it the locking-lever L and the switches 4 E A , 5 E A connected therewith, re-establishing the contact of 4 E A with 12 E A , and breaking the contact of 5 E A with 13 E A at that post. The turning to "safety" of the verifying-signal at the first signal-post 70 notifies the engine-driver that he may proceed with his train, and the turning of the shaft G at that post carries with it the strip or brush E' , Fig. 32, and leaves it resting at the limit of its upward movement on the contact E^2 . If, now, the train be allowed to proceed, on passing the first signal-post the points 1 T and 2 T of the track-circuit closer B will be 80 brought into contact, and a current from a source of electricity, B^4 , at that post will traverse the local track-circuit through the magnet D and the contacts 2 T 1 T to ground. The passage of this current through the magnet D will cause it to attract its armature into 85 contact with the fixed contact-point E , and a current will now pass from the source of electricity B^4 through the magnet D , the contact E , the armature of the magnet D , the power-releasing magnet D' , fixed contact E^2 , brush or strip E' , and power-releasing magnet D^2 to ground. The passage of this current through the magnets D' D^2 will cause them to attract 90 their armatures, and now currents will pass from a source of electricity, as at B^3 B^5 , through contacts 3 E , F^3 , and 1 E to signaling-circuit eastward, and through 3 W , F^3 , and 1 W to signaling-circuit westward. The effects of the current eastward would be similar in all respects to those of second current transmitted from initial station, except that it would affect posts 2 and 3 instead of posts 1 and 2, and the effect of the current westward would be to drop an east rear signal at the initial station, if one had been left displayed; but the armatures of the magnets D' and D^2 , having 100 been attracted, produce the further effect of releasing the power stored by the electric motor; the heavy weight H descends, carrying with it that arm of the bifurcated lever I with which shuttle-bolt K^3 is engaged; the lug I^7 makes contact with the arm carrying the lighter weight H^3 , raising it, (see Fig. 5;) the beveled sector I^5 , Fig. 7, which is formed on 105 the bifurcated lever I and meshes with the beveled wheel M' of shaft N' , imparts to said shaft a half-turn. The rag-wheel R , being fixed to this shaft, turns with it. The upward projection R^3 of this wheel, after completing 110 a fourth of a revolution, makes contact with the downward projection S' of the boss T , and through it imparts to the shaft N^3 of the rear signal a quarter-turn movement, bringing one notch of the crown-sector U' into engagement with the armature of the magnet D^6 , at same time the beveled sector U , meshing with beveled sector V , turns the cam-shaft W , raising 115 the weight H^7 , which is held in its sus- 120

125

130

135

pended position by the armature of magnet D^3 , which engages with a notch in the crown-sector U' , and raising the switches $1 E R$, $2 E R$ out of contact with $4 E R$, $5 E R$, Fig. 32, and 5 into contact with $3 E R$ and the upper contact of $2 E R$, which has no electrical connection, and is not shown. The turning of rag-wheel R , Fig. 7, also imparts to the rag-wheel R' , through the chain belt R'' , a half-turn, 10 and this carries with it the movable arm Y , Fig. 13, against the upward projection Y^2 , on which the downward projection a of the wheel Z is at rest. The wheel Z is therefore also given a half-turn, and as it meshes with 15 the beveled sector d of cam-shaft W^2 , Fig. 7, said cam-shaft and the cam-sleeve mounted thereon are thereby restored to their normal positions. The signal-locking arm e is engaged with the armature f of the magnet D^3 , 20 and the weights H^4 and H^5 , Fig. 8, are thus left suspended in their normal positions. In restoring the locking-arm escapement, Fig. 31, to its normal position the gravity-dog k passes over the cam formed on the locking-lever l , but without depressing it, as before, the dog being so pivoted between the standards j , Fig. 30, as to operate in one direction only. The heavy weight H descends until the shuttle-arm K is restored to its normal position, 25 when, the shuttle having been forced inward by the cam Q' compressing the shuttle-spring K^5 , and the bearing Q^3 being cut away at this point, the shuttle-bolt K^3 , Figs. 19 and 20, is forced inward, breaking engagement with the 30 hook I^4 of lever I , Fig. 9, and projecting its inner end into the path of the teeth J' of the wheel J . The lever I being loosely mounted on the shaft G , and the weight H^3 being now suspended, said lever is thereby restored 35 to its normal position, and through it the rag-wheels $R R'$ to their normal position. By this action of the power-receiving mechanism a rear signal, s^2 , has been displayed, and power (weight H^3) stored to conceal said signal, when 40 released, from the armature of the magnet D^3 by an electric impulse from a distant point. The verifying-signal s has been restored to its normal position of "danger," and an advance signal has been concealed, the bolt X' has been 45 thrown forward into engagement with the wheels $Z Z'$, but so loosely engaged with them that an advance signal may be unlocked by a following train, but cannot be displayed until said bolt is withdrawn by the concealing of 50 the rear signal. The rag-wheels $R R'$ having been restored to their normal position, the advance and rear signals are left free to respond to currents from distant points, and the power-receiving mechanism has been restored to 55 its normal position. The passing of the train by the second signal-post will be in all respects similar in its effects, except that the current imparted to the line westward will enter the first signal-post, where the east rear signal 60 has been left displayed at $1 E$, and pass thence through F^3 , $2 E$, $4 E$, $12 E A$, $4 E A$, $6 E A$, $15 E A$, q^3 , q' , r' , $1 E R$, $3 E R$, the magnet D^3 ,

and thence to ground. The passage of the current through the magnet D^3 will cause it to attract its armature, releasing the crown-sector U' , and the rear signal s^2 , actuated by the suspended weight H^3 , will be restored to its normal position, and so on throughout the series. An advance signal having been displayed at a given post by a train moving 70 east, a train moving west cannot display an advance signal at that post, because the circuit will be broken at $8 E A$; and a rear signal having been displayed at a given post, a following train may unlock, but cannot display an advance signal on that post, because the advance-signal mechanism is locked by a bolt, X' , that can be withdrawn only by the concealing of the rear signal. Thus is secured an entire unoccupied block between 75 any two trains on same track, whether moving in the same or in opposite directions. The effect of this arrangement on the visual signals is more clearly apparent in Fig. 34. Post No. 1 is shown with signals in normal 80 position. At No. 2 a rear signal, s^2 , is displayed to guard the eastward-moving train (represented by an arrow) between 2 and 3. At No. 3 an advance signal, s' , is displayed, and the verifying-signal s is turned to "safety," 85 which will notify the engineer that the track is clear to station 4. At 4 the east advance signal s' appears, and at 5 the advance signal s of a west-bound train appears. Neither can therefore operate advance signals beyond 90 those already displayed. The verifying-signals will stop the east-bound train at 4 and the west-bound train at 5, thus leaving the block between 4 and 5 unoccupied. Between posts 95 7 and 8 is indicated another west-bound train with rear signal displayed at 8, and advance signal displayed at 7. In passing post 8 it has unlocked advance signal at post 6; but the same cannot be displayed (as before explained) until the rear signal displayed on that post is 100 concealed. The verifying-signal at 7 will therefore remain at "danger," and the rear train will consequently be stopped at post 7 until the forward train has passed post 5 and dropped its rear signal at post 6, thus securing 105 an entire unoccupied block between two trains moving in the same direction over the same track. At post 9 the signals are again shown in their normal position.

In Fig. 33 is shown a theoretical diagram of 110 the connections for operating a special distant signal, normally held at "safety," the displaying and concealing of which are effected by electric impulses transmitted from the same or different distant points. In this figure, B^{10} 115 B^{11} B^{12} represent track-circuit closers or manual switches at distant points, as preferred; B' , a source of electricity; D' , a power-releasing magnet at the signal-post; D^3 , a signal-releasing magnet; D^{10} , a switching-magnet; D^{11} , 120 D^{12} , an electro-magnet at stations from which the distant signal is operated; P , an electric motor; J , the compound wheel of power-receiving mechanism; I , a bifurcated lever of the

power-receiving mechanism with hook I' and retracting-spring I^3 ; E' , a metal brush or strip; E^2 , a fixed contact for same, with insulating-surface at the limit of its upward movement.

5 Shuttle-arm K and shuttle-bolt are made and operated as before described. The switch or circuit-closer B is normally in contact with the fixed contact $1 T$. If this switch be depressed, a current will pass from a source of electricity 10 at that point through the contact $2 T$, the switch B^{10} , and line-conductor to distant signal-post, and thence through the switch $1 D$, contact $2 D$, the signal-releasing magnet D^5 , armature of the magnet D' , and the contact $5 D$ 15 to ground, releasing the distant signal, which will be displayed by a normally-suspended weight, as in the case of rear signals in the system before described. The cam-shaft W is geared, as before, to the signal-shaft, and the locking-arm e is rigidly mounted thereon. The turning of this cam-shaft will therefore raise the free end of switch $1 D$ out of contact with $2 D$ and into contact with $3 D$. If, now, the switch B^{10} be allowed to rise to its normal 20 position, a current will pass from a source of electricity, B' , at the distant signal-post to and through the motor P , the fixed contact E' , movable brush or strip E' , the switching-magnet D^{10} , the contact D^3 , the switch $1 D$, the switch B^{10} , contact $1 T$, verifying-magnet D^u , and thence to ground. From the contact D^3 this 25 current has a momentary ground-connection through D^4 and magnet D' ; but this connection is instantly broken, since the passage of this current through the switching-magnet D^{10} will cause it to attract its armature, thus breaking contact at $4 D$. The passage of this current through the electric motor P will, as before, store power for the concealing of the distant signal, and the action of the motor will be stopped 30 as soon as the necessary power has been stored by the movable strip or brush E' passing off the metal surface and onto the insulated surface of the fixed contact E^2 . The cessation of 35 this current will allow the armature of magnet D^{10} to rise to its normal position, thus re-establishing contact at $4 D$. If, now, the switch $1 T$ at the same or at another distant station be depressed, a current will pass from a source 40 of electricity, B' , at that point through the contact $2 T$, the switch B^{10} , switch $1 D$, contact $3 D$, armature of magnet D^{10} , contact $4 D$, and thence through power-releasing magnet D' to ground, releasing the stored power, by which 45 the displayed signal is immediately turned to "safety," in which position it is locked by the signal-locking arm e , which engages with the hook on the armature of magnet D' ; and the power-receiving mechanism and electrical 50 connections are restored to their normal positions. The electro-magnets D^u at stations from which distant signals are operated may be used to give audible or visual verification of the display of the distant signal, and the 55 same or similar magnets in the same circuit may also be used in connection with any locking device for draw-bridges, switches, &c.

It is manifest that the motor may be used to display a normally-concealed signal, at same time storing power to conceal it; or such signal may be both displayed and concealed by the direct action of the motor, if preferred. The independent light-controlling circuit may be run through every local telegraph-office along the line of railway, and telegraphic communication may then be established between any signal-post and any one of such local offices.

The electric lamp may be, and is preferably surrounded by a glass globe. Two opposite segments, ninety degrees each, corresponding to the displayed position of the verifying signal, may be red; one segment, ninety degrees, corresponding to that edge of the verifying-signal which is turned toward the approaching train when said signal is concealed, may be white, and the remaining segment, ninety degrees, opposite to this, blue, for instance.

Having thus described the construction and operation of my device, what I claim is—

1. An electric-signal system for railways in which each signal station or post is provided with an automatically-reversible electric motor connected with a source of electricity, and with a two-way reciprocating mechanism for actuating the signals at such posts or stations, substantially as and for the purpose set forth.

2. An electric-signal system for railways, consisting of a series of signal stations in normally independent circuits, each station having an automatically-reversible electric motor and signal-actuating mechanism by means of which the setting of an advance signal at a second advance-signal post by an electric impulse imparted to the signal-circuit by a moving train completes a circuit from a source of electricity at said second post to and through an electric motor located at the first post in front of the passing train, substantially as and for the purpose set forth.

3. An electric-signal system for railways in which each station or post is provided with one or more vertically-pivoted two-way-reciprocating signals, substantially as described, an electric motor connected with a source of electricity, and signal-actuating mechanism having electrical attachments connected with the motor and source of electricity, said motor acting through electric impulses to store power in said actuating mechanism, substantially in the manner and for the purpose set forth.

4. An electric-signal system for railways in which each station or post is provided with one or more signals and signal-actuating mechanism and an automatically-reversible electric motor connected with a source of electricity, said motor acting to store power in the signal-actuating mechanism for displaying the rear signal and concealing the advance signal, and at the same time actuating the verifying-signal at that post, substantially as and for the purpose set forth.

5. An electric-signal system for railways in which each station or post is provided with

- one or more signals, signal-actuating mechanism, and an automatically-reversible electric motor connected with a source of electricity, the motor at a given post acting to store power in said mechanism for displaying a rear signal, concealing an advance, and turning a verifying-signal at that post, a train on passing said post automatically releasing the stored power, the signal mechanism thereby displaying the verifying and rear signals and concealing the advance signal at that post, and at same time connecting the advance-signal circuit with a local source of electricity, displaying an advance signal at the second post in advance thereof, and connecting a local source of electricity with a rear-signal circuit, thereby concealing the rear signal at the post last passed, substantially as and for the purpose set forth.
6. An electric signal system for railways, each station of which is provided with one or more signals, an automatically-reversible electric motor, and signal-actuating mechanism, and in which the displaying of an advance signal at a second post in advance of a moving train connects a source of electricity at that post with a motor at the first post in advance of the train, said motor automatically breaking the motor-circuit as soon as the necessary power has been stored for actuating the signal mechanism at said post, the cessation of said current permitting the armature of an electro-magnet at the advance post to rise and couple the normally-independent signal-circuits terminating at that post, thus completing the signaling circuits from the post next to be passed by the train to second post in advance thereof, substantially as and for the purpose set forth.
7. An electric-signal system for railways, each post of which is provided with one or more signals and actuating mechanism therefor, and an automatically-reversible electric motor, the posts being electrically connected, the signal mechanism and its electrical connections at one post automatically controlling the signal mechanism and the electrical connections of one rear and two advance posts in such manner that one train cannot affect them when another train has an advance or rear signal displayed thereon, thus always securing an entire block between any two trains on the same track, whether moving in the same or opposite directions, substantially as set forth.
8. An electric railway - signal system in which each advance signal is normally held at "safety" and operated by trains moving in either direction through the intervention of electrical connections and signal-actuating mechanism in two sets of parts only one of which operates at one time, and so operates that the signal is thereby turned to the right or left, according to the direction of the moving train, with the safety side of said signal in each case turned toward the approaching train, as and for the purpose described.
9. An electric-signal system for railways, each post of which is provided with one or more signals, and mechanism for actuating the same, and electrical connections, and in which each advance signal is adapted to be displayed in either of two directions, according to direction of approaching train, by the release of a normally and automatically stored power in said mechanism.
10. An electric-signal system for railways in which each signal post or station is provided with one or more signals, and actuating mechanism controlled by an automatically-reversible electric motor electrically connected with such mechanism, and a source of electricity, the operation of said motor at each post being dependent upon the position of the advance signal next beyond it, and the direction of its rotation determined by the direction from which it receives current, substantially as and for the purpose set forth.
11. An electric railway - signal system in which each signal-post is provided with a power-receiving and signal-actuating mechanism and an automatically-reversible electric motor which, when turned in one direction by an electric impulse, stores power (in said mechanism) that, when released, will display an east rear signal and conceal an east advance signal, and turned in the other direction will store power that, when released, will display a west rear and conceal a west advance signal, and turned in either direction will turn the verifying-signal from its normal position of "danger" to "safety," and vice versa, substantially as and for the purpose described.
12. An electric-signal system for railways in which each signal - post is provided with one or more signals, actuating mechanism therefor, and an automatically-reversible electric motor the driving-current of which is automatically broken by a cut-out in the motor-circuit as soon as the required power in the power-receiving part of the signal mechanism has been stored by said motor, substantially as and for the purpose described.
13. In an electric railway-signal system, an automatically-reversible electric motor at each signal-post, for concealing displayed signals through the intervention of suitable mechanism and electrical connections.
14. In an electric-signal system for railways, an automatically-reversible electric motor at each post, for displaying concealed signals through the intervention of suitable mechanism and electrical connections.
15. In an electric-signal system for railways, an automatically-reversible electric motor at each signal-post for storing power that, when released electrically, will actuate visual signals through the intervention of suitable electrical and mechanical connections.
16. In an electric-signal system for railways, an automatically - reversible electric motor with suitable electrical and mechanical connections, for operating electric latching and switching devices.

17. In an electric-signal system for railways, an automatically-reversible electric motor with suitable electrical and mechanical connections for storing power that, when released electrically, will actuate electric latching and switching devices.
18. A system of electric signals for railways in which each post is provided with an automatically-reversible electric motor, as described, in combination with one or more signals and with suitable electrical and mechanical connections for actuating said signals and signal mechanism.
19. An electric-signal system for railroads in which each signal-post is provided with one or more signals, signal-actuating mechanism, and a local lighting-circuit passing through two switches, one of which is adapted to be closed by the display movement of one or more of said signals, and the other of which is adapted to be closed by an electro-magnet in an independent light-controlling circuit, but the concurrent closing of both of which is necessary to direct a lighting-current from a source of electricity through an electric lamp to ground at that post, substantially as and for the purpose set forth.
20. In electric railway-signals, a vertically-pivoted two-way reciprocating visual signal provided with electrical and mechanical devices for displaying and concealing same, substantially as and for the purpose set forth.
21. In a system of electric railway-signals, the combination, with an automatically-reversible electric motor and electro-mechanical signal-actuating mechanism, of a vertical oscillating verifying-signal normally displayed, but that may be concealed by an electric current from either of two distant and opposite points.
22. In a system of electric railway-signals, a vertical oscillating verifying-signal normally displayed, but adapted to turn through an angle of ninety degrees in a horizontal plane in either direction from its normal position, and that, through the intervention of mechanical and electrical connections, as described, may be turned by an electric current from either of two distant and (with respect to the railroad-track) opposite points, and that will be turned in one direction or the other according to the direction from which such current is received.
23. In a system of electric railway-signals, a single vertical oscillating verifying-signal at each post, normally displayed, but adapted to turn ninety degrees in either direction from its normal position through the intervention of mechanical and electrical connections, as described, the direction of its movement being determined by the direction from which current is received, and that when so turned to indicate "safety" will also indicate the direction from which the train that it signals is approaching.
24. In a system of electric railway-signals, the combination, with electro-mechanical signal-actuating devices electrically connected

forward and rearward, as described, of a single vertical oscillating verifying-signal at each signal post or station, normally displayed, but adapted to turn ninety degrees in either direction from its normal position, which movement can be effected only by the display movement of advance signal mechanism at a distant post in a direction opposite (with respect to railroad-track) to that from which such advance signal mechanism is operated.

25. In a system of electric railway-signals, comprising an advance and rear signal and a verifying-signal at each post, an advance-signal mechanism in two sets or parts, each provided with a set of automatic electric switches, as described, one part of which is operated by an electric current from a distant point in one direction only and the other by an electric current from a distant point in the opposite direction.

26. In a system of electric railway-signals, an advance signal mechanism in two sets or parts, each part comprising a normally-stored power detained by a locking-arm and electric latching device, but capable of being released by an electric impulse from a distant point, in connection with a cam-shaft for operating electric switches.

27. In electric railway-signals, a cam-sleeve loosely mounted on each cam-shaft of the advance signal mechanism provided with a separate normally-stored power detained by a locking-arm escapement which normally rests against the locking-arm of the cam-shaft on which said cam-sleeve is mounted, but which, when said locking-arm has been released, has a step-by-step movement controlled by the same electric latching device that controls the forward movement of said cam-shaft, and is restored to its normal position by the restoration of the cam-shaft to its normal position.

28. In electric railway-signals, the combination, with one or more signals and signal-actuating mechanism, of a cam-sleeve for operating electric switches, loosely mounted on each cam-shaft of the advance signal mechanism, adapted to be actuated by a separate normally-stored power, and normally detained by the locking-arm of said cam-shaft, against which it rests, but which, when said locking-arm has been released, has a step-by-step movement controlled by an electric latching device in such manner that the direct effect of a first electric current by releasing the locking-arm of the cam-shaft will be to give to this locking-arm escapement its first forward movement, its reflex effect at cessation of first current will give a second forward movement, the direct effect of a second electric current will give a third forward movement, and its reflex effect at cessation of second current will give its fourth and final forward movement.

29. In electric railway-signals, the combination, with one or more signals and signal-actuating mechanism, of a cam-sleeve loosely mounted on each cam-shaft of an advance signal mechanism adapted to be actuated by a

separate normally-stored power and normally detained by the locking-arm of said cam-shaft, but which, when said locking-arm has been released, has a four-step forward movement, at the second of which it operates indirectly two electric switches connecting a local source of electricity with line-wire to rear, and at the fourth of which it operates directly one electric switch establishing a local ground (or return circuit) connection for a like current from a distant post in advance.

30. In electric railway-signals, the combination, with a cam-sleeve having a step-by-step movement, of a gravity dog so pivoted to lugs or standards formed on said cam-sleeve as to have an independent radial movement with reference to said cam-sleeve in one direction only, and a locking-lever pivoted at one end and so adjusted with reference to said dog as 20 to be depressed by said gravity-dog in its forward movement, but not disturbed by it in its return movement.

31. In electric railway-signals, the combination, with a cam-sleeve having a step-by-step movement and a gravity-dog so pivoted thereto as to have an independent radial movement with reference thereto in one direction only and a locking-lever pivoted at one end and so adjusted with reference to said gravity-dog as 30 to be depressed by its forward movement but not disturbed by its return movement, of a spring-latch by which said locking-lever, when depressed, is detained, and a connecting-rod by which said locking-lever is rigidly connected with two or more electric switches that are thereby depressed when said locking-lever is depressed, and so remain till said locking-lever is allowed to rise to its normal position.

32. In electric railway-signals, a switch-controlled magnet and its armature, connected with a local source of electricity and one or more electric switches, in combination with a spring-latching device for locking said switches in a depressed position and completing the 45 circuit through said magnet and line-conductor to a distant point rearward, a current through which circuit causes said magnet to attract its armature, which will at once displace said latching device, but still hold the 50 switches depressed until the circuit is broken at the distant point, when the armature and the switches will rise together to their normal position and the latching device assume its normal position.

55. 33. In a system of electric railway-signals, a normally-independent circuit extending from one signal-station to the one next adjacent to it, each end terminating in a movable switch adapted to move between two fixed contacts, 60 one of which is connected with a source of electricity, and the other is normally connected through electric signal-releasing devices to ground or other return circuit, and against the latter of which said movable switch normally rests, whereby the connection of the movable switch with the source of electricity at one post will cause a current to pass to and through

the electric signal-releasing devices at the other post.

34. A system of electric signals for railways 70 in which each signal-post is provided with one or more signals and actuating mechanism therefor, substantially as described, and an electric lamp in a normally-open lighting-circuit, said lighting-circuit being under the control of an independent circuit in so far only as to control the lamp irrespective of the position of signals in day-time, or when no lights are required, said independent circuit passing through an electro-magnet at each signal-post, 80 the armatures of which magnets are portions of the normally-open lighting-circuits for their respective posts, the magnets, when energized by a current of said independent circuit, attracting their armatures from contact 85 in the normal lighting-circuit, thus breaking the lighting-circuit simultaneously at each post, so that, though signals be displayed, no light will appear, substantially as and for the purpose set forth. 90

35. A system of electric signals for railways in which each signal post or station is provided with one or more signals and actuating mechanism therefor, and an electric lamp the lighting-circuit of which is controlled by an 95 independent circuit, and a cut-out at each post in said independent circuit for the reception of a plug connected with a telegraphic outfit, so that said independent circuit may be used at any time for telegraphic purposes without 100 disturbing the signaling-circuits, substantially as and for the purpose set forth.

36. In a system of railway-signals, a two-way reciprocating power-receiving mechanism and one or more signals adapted to be 105 actuated thereby, in combination with a motor and source of energy, whereby power may be stored that, when released, will display concealed signals, or conceal displayed signals of trains moving in either direction over a given 110 track, and at the same time actuate signal mechanism and electrical appliances, substantially as shown and described.

37. In a system of electric signals for railways, an electro-mechanical power-receiving 115 mechanism supported on a bed-plate in the bottom of the signal-box, a main shaft about which said mechanism is mounted, a shuttle-arm having an automatic locking and releasing shuttle, a weight-raising lever, and one or 120 more automatic cut-outs for electric circuits, a compound wheel geared with an electric motor, a bifurcated two-armed lever normally locked in both directions, and two arms carrying the heavier weights by the suspension of 125 which power is stored, and in such position that when the main shaft is turned from its normal position it will raise one of them without disturbing the other, and two arms carrying lighter weights in such position that when 130 the bifurcated lever is moved from its normal position it will raise one lighter weight without disturbing the other, and two cam-plates for changing the position of the shuttle with-

in said shuttle-arm during its movement and while the shuttle-bolt is held in a fixed position relative to said arm.

38. In electric signals for railways, an electro-mechanical signal-actuating mechanism in two sets or parts for advance signals, consisting of a rag-wheel, R', a pair of slotted wheels mounted upon a shaft in such position that the turning of the rag-wheel in either direction from its normal position will affect but one of said slotted wheels, and then only to restore it to its normal position, a cam-shaft geared to each wheel, with normally-stored power detained by an electric latching device, a signal-shaft pivotally mounted upon the shaft carrying the rag and slotted wheels, with a beveled wheel rigidly mounted thereon in such position that the movement of either slotted wheel from its normal position will 20 turn the signal-shaft, but in opposite directions, and a cam-shaft geared to said beveled wheel and provided with a suitable weight so adjusted that the turning of said cam-shaft from its normal position will raise said weight, thus storing power to restore the signal-shaft to its normal position as soon as released from the heavier weight by which it was turned away therefrom, as and for the purpose set forth.
39. In electric signals for railways, an electro-mechanical rear-signal mechanism consisting of a rag-wheel, R, rigidly mounted on a shaft or stud, and a rear-signaling shaft pivotally mounted on the top of said shaft, and on which is rigidly mounted a cam-boss, S, in such position that the turning of said rag-wheel one-half around in either direction will turn said signal-shaft one-fourth around in the same direction, and a beveled sector to which is 40 geared a cam-shaft carrying a weight, H', that, when said signal-shaft is turned from its normal position, will be raised and suspended, and a sector with two notches diametrically opposite, and an electric latching device so adjusted with reference thereto that on the turning of said signal-shaft one-fourth around, in either direction from its normal position it is adapted to engage with said sector, and thus hold said weight in its suspended position, so 50 that when released from said latching device it will restore the signal to its normal position.

40. In electric signals for railways, the combination of an automatic electro-mechanical signaling device including advance, rear, and 55 advance-verifying signals with a local independent track-circuit and circuits to one or more distant points.

41. In electric signals for railways, the combination in one circuit of two or more signal-actuating mechanisms located at different 60 points and each having a local source of electricity and automatic switching devices whereby a mutual interdependence is established and maintained between the signals displayed and concealed thereby, substantially as shown 65 and described.

42. In a system of electric signals for rail-

ways, consisting of a series of normally-independent circuits, the combination of electro-mechanical signal-actuating mechanism at 70 each post with automatic electric switching devices, whereby normally-independent signaling-circuits without battery are automatically coupled and uncoupled in front and rear of moving trains and connected with a source 75 or sources of electricity, as required, substantially as set forth.

43. In an electric-signal system for railways, an automatically-reversible electric motor with an automatic cut-out at each signal-post 80 and electric switching devices, whereby said motor may be thrown into either of two normally-independent circuits, each of which circuits includes a source of electricity and an automatic switching device at a distant point. 85

44. In an electric railway-signal system, a series of independent circuits extending from post to post along the line of railway, each provided at either end with signal-actuating mechanism, automatic switching devices, an 90 automatically-reversible electric motor, and a source of electricity, said motors and sources of electricity being normally out of circuit, but adapted to be thrown into and out of circuit automatically by said signal-actuating 95 mechanism.

45. In electric signals for railways, a series of independent motor-circuits, each circuit extending from a given signal-post to another only, and each including a source of electricity, 100 an automatically-reversible electric motor normally out of circuit, a switch or switches for controlling the action of such motor, an automatic cut-out, and an electro-magnet and its armature at a distant point, and one or more signals and signal-actuating mechanism, whereby the action of said motor is automatically controlled, and the cessation of the driving-current automatically couples or unites at a 105 distant point two normally-independent signaling-circuits. 110

46. In an electric signal-system, as described, a series of normally-independent signaling-circuits with one or more vertically-pivoted two-way reciprocating signals, an automatically-reversible electric motor and a source of electricity at each signal-post, in combination with electrical connections and appliances whereby said normally-independent circuits are automatically utilized as motor-circuits or 120 signaling-circuits, dependent upon the conditions existing at one or more distant posts. 115

47. A signal-post with one or more vertically-pivoted two-way reciprocating signals and signal-actuating mechanism, an automatically-reversible electric motor, a source of electricity, and electrical connections to two or more distant and opposite points, a first current to which will display an advance signal toward a direction opposite to that from which 125 said current is received; the cessation of this current will unite a local source of electricity through an electro-magnet and its armature with line-wire to rear, giving out a current 130

that will drive a motor at a distant point; the cessation of this motor-current, caused by an automatic cut-out at the distant point where motor is located, will unite or couple together 5 at said post the two normally-independent signaling-circuits that terminate thereat; a second signaling-current passing over these two temporarily-united circuits will pass through this post, and its cessation will connect the 10 line forward through the electro-motor to ground at this post, thus disuniting the two normally-independent circuits that were before united, and a motor-current now traversing the circuit that includes the forward post 15 and its electro-magnet, the local electro-motor and its automatic cut-out, and a source of electricity will, through the action of said motor, conceal the normally-displayed verifying-signal, and at same time store power that, when 20 released, will display the verifying and a rear signal and conceal the advance signal; the passage of a train by this post releasing the stored power, which changes the positions of the signals thereat, as stated, leaving only a 25 rear signal displayed; and, finally, said rear signal is concealed by an electric impulse from a distant point in the direction of the receding train, and the mechanism thus restored to its normal position.

30 48. An electro-mechanical signal-actuating mechanism electrically connected with a local source of electricity and with a like mechanism at one or more distant points, including an electric motor normally out of circuit, and 35 its automatic cut-out, a two-way reciprocating power-receiving mechanism by which the power of said motor may be automatically stored by a current from a distant point, as required; a power-releasing mechanism by 40 which said stored power may be automatically utilized, as required; an advance-signal mechanism in two sets, only one of which acts at one time, but both of which are adapted to act on same signal and electric switching devices back and forth, though in opposite directions, corresponding to the direction in which the train signaled is moving, and to 45 break the forward signaling-circuit when said advance signal is displayed; a rear-signal mechanism adapted to move a given signal and electric switching devices back and forth in either of two directions, corresponding to the direction in which the train signaled is moving, and to lock the advance signal at "safety" 50 when said rear signal is displayed in either direction, and a verifying-signal normally held at "danger," but turned to "safety" by the storing of power in said mechanism, and restored to its normal position by the release of 55 said power, with an automatic cut-out adapted to break the incoming signaling-circuit in all directions when said signal is displayed, as set forth.

49. An electro-mechanical signal-actuating mechanism, electrically connected with a local source of electricity and with a like mech-

anism at one or more distant points, including an electric motor normally out of circuit and its automatic cut-out, a two-way reciprocating power-receiving mechanism by which the power of said motor may be automatically stored, as required; a power-releasing mechanism by which said stored power may be automatically utilized when required; an advance signal mechanism in two sets or parts, 70 both of which are adapted to act on same signal, but in opposite directions and at different times, as required; a rear signal mechanism adapted to move a given signal in either of two directions, as required, and a verifying-signal that indicates the position of the advance signal at a distant point beyond it, and the direction from which the train that 75 it signals is approaching.

50. In electric signals for railways, the combination, with an independent local track-circuit and electro-mechanical signal-actuating mechanism, of an auxiliary local circuit normally open at two points one of which is closed by the movement of the signal-actuating mechanism and the other by the closing of an independent track-circuit, substantially as shown.

51. In electric signals for railways, a signal-station or stationary mechanism including 95 a local source of electricity and an automatically-reversible electric motor with one or more signals and signal-actuating mechanism electrically connected to two or more distant points, whereby an advance signal may be 100 displayed from a distant point, power stored to conceal said advance signal and display a rear signal, this stored power then released, and finally a rear signal concealed from a distant point, substantially as shown.

52. An electro-mechanical signal-actuating mechanism electrically connected with a local source of electricity and with one or more distant points, consisting of an automatically-reversible electric motor normally out of circuit and its automatic cut-out, a reciprocating power-receiving mechanism, a power-releasing mechanism, a signal locking and releasing mechanism, and electro-magnets and switching devices, substantially as shown and 110 described.

53. In electric signals for railways, the combination of a power-receiving mechanism having a two-way reciprocating movement and including the compound wheel J, the shuttle-arm K, the shuttle K', the shuttle-bolt K'', the cam-plates Q, the two-armed lever I, the lighter weights H² and H³, the weight-raising lever L, and the heavier weights H H', with an electric motor, electric power-releasing devices, and one or more sources of electricity, 120 substantially as shown.

54. In electric signals for railways, the combination, with a power-receiving and power-releasing mechanism, substantially as described, a source of electricity, and electrical connections forward and rearward, of a verify-

ing signal and mechanism for advance and rear signaling, substantially as and for the purpose set forth.

55. In an electro-mechanical signal-actuating mechanism, the rag-wheel R' , the loose arm Y , the pair of slotted wheels Z Z' , with the cam-shafts W' W^2 W^3 , the cam-sleeves g g' , and their connections, substantially as described.

10 56. In an electro-mechanical signal-actuating mechanism, the rag-wheel R , the boss S , the cam-shaft W , the eccentric cam T , the eccentric strap or bolt X , and their connections, substantially as shown.

15 57. In electric signals for railways, the combination, with electro-mechanical signal-actuating mechanism and electrical connections forward and rearward, of a verifying-signal the position of which at five consecutive posts 20 more or less remote from each other may be controlled by a moving train, said signal being displayed at the two posts next in rear of such train, concealed at the first post in advance thereof, and displayed at the two posts 25 next succeeding this, substantially as shown.

58. An electric signal-actuating mechanism for railways in which each post is provided with a verifying-signal, for indicating to the engineer the "danger" or "safety" position of a distant advance signal and the position of which, 30 with reference to a moving train, is normally controlled automatically by the movement of said train, at three posts in advance and two in rear of said train, through the intervention 35 of electro-mechanical signal-actuating devices, a source of electricity, and electrical connections forward and rearward.

59. In electric railway-signals, the combination, with a source or sources of electricity, 40 an electric motor, an electro-mechanical signal-actuating mechanism, and electrical connections to one or more distant points, of a special danger signal and automatic switching devices, whereby said signal may be displayed 45 by an electric impulse from a distant point, and by the movement of which from its normal position said motor and its source of electricity are thrown into the signaling-circuit, the driving-current of said motor passing 50 over the signaling-circuit to the operating-station verifies the distant signal at that station, and by the action of the motor itself power is stored in the signal-actuating mechanism, which power may afterward be released by an 55 electric impulse from the same or another distant point, and when so released will restore said signal and signal mechanisms to their normal positions, substantially as described.

60. In a system of electric railway-signals, 60 the combination, with an advance signal mechanism in two sets or parts, and operating as described, of an electric motor, a source of electricity, and mechanism, as set forth, for normally storing power, a locking-arm, and 65 an electric latching device by which said stored power and mechanism are controlled, substantially as and for the purpose set forth.

61. In a system of electric signals for railways, the combination of an advance and rear signaling mechanism with an electric motor, 70 a power-receiving mechanism, a source of electricity, and electrical connections forward and rearward, as and for the purpose set forth.

62. In a system of electric signals for railways, the combination, with an advance and rear signal mechanism, and an electric motor, and a source of electricity at each post, of a verifying-signal at each post, as and for the purpose set forth.

75 63. In a system of electric signals for railways, the combination, with a track-circuit closer and its source of electricity, the magnets D D' D^2 and their armatures, a contact, E , the brush or strip E' and its contact E^2 , an automatical reversible electric motor, and a 80 source of electricity, of the signals and signal-actuating mechanism, as set forth.

85 64. In electric signals for railways, the combination, with the magnets D' D^2 , each having a hooked shoulder formed on the free end thereof and electrically connected, as described, of the two-armed levers F F' , normally engaged therewith, said levers being pivoted at their angles, and provided with retracting-springs F^2 , to hold them in their normal positions with 90 a power-receiving and signal-actuating mechanism and electric motor and source of electricity, as and for the purpose set forth.

95 65. In a system of electric railway-signals, the combination of a power-receiving mechanism consisting of a pair of loosely-mounted arms secured to shaft G and carrying the heavier weights H H' , a pair of loosely-mounted arms carrying the lighter weights H^2 H^3 , the bifurcated lever I , the compound wheel J , 100 shuttle-arm K , weight-raising lever L , and the insulated brush or strip E' , with a source of electricity and an automatically-reversible electric motor, as set forth.

105 66. In electric signals for railways, the combination, with a reciprocating signal-actuating mechanism, of the two-armed lever I , pivoted loosely at its angle on the shaft G , each of its arms at its outward extremity being provided with a latch, I' I^2 , to normally engage with the 110 short arms of the levers F F' , respectively, and in such manner as to affect only the downward movement of said latches, substantially as set forth.

115 67. In electric signals for railways, the combination, with a reciprocating signal-actuating mechanism, of a lever, I' , each arm of which at its extremity has a downward-projecting hook, I^4 , and provided with two bearings between which are mounted the shuttle-arm K and compound wheel J , one bearing extending upward and carrying the beveled sector I^5 .

120 68. In electric signals for railways, the combination, with the bifurcated two-armed lever I , provided with a reciprocating signal-actuating mechanism, of the weight-raising projections I^6 I^7 , projecting at right angles to the vertical plane of said lever, and the arms carrying the 125 weights H^2 H^3 , said arms resting in the path

of said projections in such positions that one or the other of them is raised whenever said lever I is moved from its normal position.

69. In electric signals for railways, the combination, with electric signal-actuating mechanism, as described, of the compound wheel J, mounted at its center upon the shaft G, and having its face divided circumferentially into two parts, J' J², as and for the purpose set forth.

70. In electric signals for railways, a shuttle, K', having laterally-projecting studs K², sliding in slots in the arm K, and projecting beyond the surface of said arm to form bearings by which the shuttle can be moved longitudinally within said arm, as set forth.

71. In electric signals for railways, the shut-

tle-arm K, pivoted to shaft G, carrying at one end the beveled sector K⁶, its other end being bored and slotted to receive the shuttle K', its cam-rollers K², the shuttle-bolt K³, and its cam-rollers K⁴, as set forth.

72. In an electro-mechanical signal-actuating mechanism, the power-releasing magnets D' D² with their armatures f and a source of 25 electricity, in combination with the two-armed levers F F', substantially as shown.

In testimony whereof I affix my signature in presence of two witnesses.

WILLIAM T. WATERS.
